UNITED STATES PATENT OFFICE.

HERBERT E. VAN DORN, OF CHICAGO, ILLINOIS.

DRAFT AND BUFFING GEAR.

1,251,942.

Specification of Letters Patent. Patented Jan. 1, 1918.

Application filed November 28, 1915. Serial No. 63,632.

To all whom it may concern:

Be it known that I, HERBERT E. VAN DORN, a citizen of the United States, and a resident of the city of Chicago, in the county of Cook and State of Illinois, have invented certain new and useful Improvements in Draft and Buffing Gears; and I do hereby declare that the following is a full, clear, and exact description of the same, reference being had to the accompanying drawings, and to the numerals of reference marked thereon, which form a part of this specification.

It is an object of this invention to construct a draft and buffing gear embodying a number of friction elements so designed and constructed as to withstand draft and buffing stresses equally well, and requiring only a small travel of the parts to absorb the stress imparted to the gear.

It is also an object of this invention to construct a combination draft and buffing gear wherein a number of friction elements are movably associated with one another and capable of movement against spring pressure, which acts to increase the friction between said elements to resist and absorb stress imparted to the gear.

It is furthermore an important object of this invention to construct a combination draft and buffing gear wherein certain of the parts are movable inwardly against inclined abutment walls with increasing friction and against spring pressure to resist and absorb stress imparted to the gear, said elements when moving inwardly toward one another having sliding engagement with means associated therewith to further increase the friction of resistance in a manner such that the friction pressure between said latter means increases with the increase in stress applied to the gear.

It is finally an object of this invention to construct a heavy duty draft gear embodying a plurality of friction elements movable with respect to one another and provided with an eccentric take-up mechanism to compensate for wear between the friction elements and avoid looseness in the gear.

The invention (in a preferred form) is illustrated in the drawings and hereinafter more fully described.

In the drawings:

Figure 1 is a fragmentary side elevation with parts removed and parts shown in sec-

tion of a gear embodying the principles of my invention.

Fig. 2 is a section taken on line 2-2 of Fig. 1.

Fig. 3 is a detail section taken on line 3-3 of Fig. 2, with parts shown in elevation.

Fig. 4 is a view similar to Fig. 3, showing the parts in an adjusted position when a draft stress is imparted to the gear.

Fig. 5 is an interior face view of one of the longitudinally movable abutment friction members with the ends thereof shown in section.

Fig. 6 is an end view of the abutment members showing the vertical and horizontal transverse friction plates associated therewith.

Fig. 7 is a detail view showing the toothed wheel on the adjusting eccentric.

As shown in the drawings:

As shown in Figs. 2, 3, and 4, the center channel sills, denoted by the reference numerals 1, of the car upon which the gear is mounted, are utilized, and held rigidly in stationary position flat against the inner surfaces of said sills by means of stops 2. Riveted to the sills, are a pair of similarly constructed stationary friction elements 3, each provided at its opposite ends with abutments 4 and 5, respectively, which, at their ends, abut against said stops 2, and intermediate said abutments provided with outwardly projecting angled frictional abutment members, one inclined face of each of which is denoted by the reference numeral 6, and the other, by the reference numeral 7. Riveted or otherwise rigidly secured across the top flanges of the channel sill members 1 and 2, is a plate 8, and similarly disposed beneath the bottom flanges of said sill members is another plate 9, as clearly shown in Figs. 1, 2, and 3. Fitted movably against said respective stationary friction elements 3, are a pair of similarly constructed friction elements, each denoted by the reference numeral 10, and provided with a plurality of angled abutments 11, along one surface, adapted to interfit with the abutments 6-7, of said stationary elements. Each of said movable friction elements 10, is recessed on its inner face to afford inclined walls 12, and fitted between said respective friction elements 10, within the recessed portions thereof against said inclined walls 12, are upright wedge mem-

bers 13 and 14, respectively, provided with a pair of lugs 15, to afford retaining means for two sets of coiled compression springs, one spring of each set coiled within the other and said springs denoted by the reference numerals 16 and 17, respectively.

At the forward and rear ends of each of said movable friction elements 10, at the top and bottom portions thereof, are extensions 18, which are clearly shown in Fig. 5, and receive inserted therein, friction plates 19, in spaced relation. Laid in vertical position and extending horizontally within the gear and interposed between said respective friction plates 19, are a series of plates 20, with their edges adjacent to said stationary elements 3. Adjacent the forward abutments or stops 4, is a front follower plate 21, which rests against the outermost plate 20, of the forward group of plates 19-20, and another follower plate 22, is mounted between said stationary members 3, lying flat against the outermost friction plate 20, of the rear group of friction plates, disposed adjacent said rear stops 5. Disposed at the rear of said follower plate 22, is a block 23, and at the rear of said block 23, is another block 24, said blocks 23 and 24, having registering curved recesses therein into which fits a horizontal eccentric 25.

Extending between said upright channel sill members 1, between the top and bottom plates 8 and 9, secured thereon, is a long integral yoke 26, surrounding the elements 35 of the gear. The forward follower plate 21, bears against the forward end of said yoke and at the rear curved end of said yoke the block 24, which is curved complementally therewith, fits closely therein, so that stresses, 40 either buffing or draft, as the case may be, imparted to said yoke from the drawbar of the car, cause movement thereof, either forwardly or rearwardly, as the case may be, with a consequent resistance to such movement by the co-acting friction elements comprising the gear.

As clearly shown in Figs. 4 and 7, a toothed washer or wheel 27, is provided on each end of the eccentric 25, by which the 50 eccentric is held in an adjusted position and due to the fact that the toothed wheels are locked to the eccentric by split pins 28, and notches between the teeth of the wheels are engaged over lugs 29, formed on the block 23, 55 rotation of the wheels and movement except for adjustment of the eccentric is prevented. Means is also provided for holding the parts of the gear assembled during installation of the same. For this purpose registering 60 apertures are provided through the members 3, 10, 13 and 14, through which horizontal transversely disposed assembly bolts 30, are inserted and afterward removed when the gear has been put in place upon a car. For 65 convenience of installing, holes are cored

through the wedges and the movable stationary friction members. The holes are cored large at the outer sides of the stationary friction members 3, to allow room for the head on one side and a nut on the other of 70 an assembled bolt 30, to extend through the registered cored holes. The bolts are put in and tightened to draw the stationary friction members together the proper distance, to allow them to slip into place between the 75 sills 1, and stationary stops 2, and as the parts are made full size, when the draft gear is in normal position, the parts will be under an initial stress. Any side wear on the friction members will thus be automatically 80 taken up. Holes are provided in the sills to correspond with the position of the bolts 30, when the draft gear is finally placed in position, so that said assembly bolts holding the draft gear together may be taken 85 out. The holes may also be utilized to replace and use the bolts to facilitate dismounting the draft gear.

The operation is as follows:

The normal position of the elements of the 90 draft gear is shown in Fig. 3, wherein, due to the fact that no stress is imparted to the gear, the compression of the respective springs 16 and 17, serves to impel the wedge members 13 and 14, away from one another, 95 which in turn act to impel the movable friction elements 10, laterally apart, and into interfitting relation with the abutments 6-7, on the stationary members 3, secured against the sills of the car between the stops 2. 100 However, in the event that a draft stress is imparted to the gear, thus causing the yoke 26, to be pulled forwardly, the angled abutments 11, on the respective movable friction elements 10, ride upwardly upon the 105 inclined surfaces 7, of the stationary members 3, thus causing said elements 10, to be forced inwardly toward one another which in turn causes the wedge members 13 and 110 14, contacting the angled surfaces of said wedge members 10, to be thrust toward one another, compressing the springs 16 and 17, thereby. Of course, in a draft stress forward movement of the element 10, is resisted, and due to the fact that stress is applied at the rear of the gear through the 115 blocks 23 and 24, and the rear follower plate 22, the rear group of plates 19 and 20, is subjected to considerable pressure. Due to the fact, however, that said 120 movable elements 10, riding upwardly upon the inclined surfaces 7, of the stationary members, are caused to slide toward one another, an enormous friction is exerted between the plates 19, mounted in said movable members or elements 10, and the plates 20, interposed therebetween. As a consequence, the number of surfaces which are in contact with one another between the respective parts of the gear, and the pressure to 125 130

which the same are subjected, set up an enormous resistance to movement of the elements of the gear, so that the draft is absorbed. An exactly similar operation takes place 5 when the buffing stress is transmitted to the gear, the only difference being that the forward group of plates 19 and 20, is subjected to the pressure and co-act with the movable elements 10, and fixed members 3, as well as 10 the wedge blocks 13 and 14, and springs therebetween, in resisting buffing stress and absorbing the same. In the event that the many contacting surfaces of the parts of the gear become worn after constant use, thus 15 resulting in a looseness of the parts, the eccentric 25, may be rotated an amount sufficient to increase the distance between the block 23, and the block 24, thus thrusting the elements of the draft gear snugly within the 20 yoke 26. This operation is performed by removing the split pins 28, from the toothed wheels 27, and withdrawing the wheels out of engagement with the lugs 29, then rotating the same and the eccentric therewith 25 and engaging the wheels again with the lugs 29, after which the split pins 28, are replaced to retain the wheels locked on the eccentric, and the eccentric locked in position.

I am aware that various details of construction may be varied through a wide range without departing from the principles of this invention, and I therefore do not purpose limiting the patent granted otherwise than necessitated by the prior art.

35 1. I claim as my invention:

1. In a draft gear of the class described stationary members, a series of inclined abutments on each thereof, movable members disposed therebetween, a series of inclined abutments on each of said movable members 40 adapted to frictionally interfit with the inclined abutments of said stationary members, wedge members interposed between said movable members independently of said stationary members, and springs disposed between said wedge members to resist compression thereof by movement of said movable members with respect to said stationary members.

50 2. In a draft gear of the class described stationary members having inclined friction surfaces thereon, movable members complementally shaped to interfit with said stationary members and when moved with respect thereto to ride upon the inclined surfaces thereof, said movable members when so moved, moving toward one another, wedge members disposed between said movable members arranged to be thrust toward one 55 another when said movable members move toward one another, springs disposed between said wedge members to resist movement thereof toward one another, and a plurality of groups of friction plates mounted 60 at the ends of said movable members adapted

to slide on one another and acting to frictionally assist in resisting movement of the parts of the gear.

3. In a draft gear of the class described stationary members, movable members disposed therebetween capable of diagonal movement with respect to said stationary members and when moved moving toward or away from one another, wedge members disposed between said movable members, a 70 plurality of groups of coiled springs bearing at their ends against said respective wedge members to thrust the same apart and resist inward movement of said movable members toward one another, groups of friction plates at each end of said movable members adapted to slide upon one another with frictional resistance when said movable members move inwardly toward one another, and eccentric means adjustable to take up 80 for wear on the parts of the gear.

4. In a device of the class described the combination with the sills of a car, of stationary members secured thereon, movable members mounted adjacent said stationary 90 members movable toward one another when moved from normal in either direction longitudinally of said stationary members, interfitting abutments on said movable and stationary members to cause a diagonal 95 movement of said movable members to take place toward one another when moved away from normal with respect to said stationary members, resilient means interposed between said movable members to resist inward movement of one another toward one another, and a yoke disposed about said movable members to impart movement thereto due to draft or buffing stresses imparted to 100 the gear.

5. A draft gear comprising stationary and movable friction elements, and eccentric means for adjustment for wear theretwix.

6. A draft gear comprising stationary and movable friction members with said movable friction members capable of movement in opposite direction with respect to said stationary members while frictionally in contact therewith, co-acting means formed on said 110 stationary and movable members to impose a movement of said movable members toward one another when moved relative said stationary members in either direction, and spring resisted wedge members disposed between said movable members operating to resist movements thereof toward one another.

7. In a draft gear of the class described, stationary stops, stationary members having inclined friction surfaces thereon, movable members complementally shaped to interfit with said stationary members and when moved with respect thereto to ride upon the inclined surfaces thereof, said 120

movable members when so moved, moving toward one another, wedge members disposed between said movable members arranged to be thrust toward one another 5 when said movable members move toward one another, springs disposed between said wedge members to resist movement thereof toward one another, and a plurality of groups of friction plates mounted at the 10 ends of said movable members adapted to slide on one another and acting to frictionally assist in resisting movement of the parts of the gear.

8. In a draft gear of the class described, 15 stationary stops, stationary members, inclined abutments thereon, movable members disposed therebetween, inclined abutments on said movable members adapted to interfit the inclined abutments of said stationary members, wedge members interposed between said movable members, springs disposed between said wedge members to resist compression thereof by movement of said movable members with respect to said 25 stationary members, and friction plates associated with said stationary and movable members to assist in resisting movement of the gear parts.

9. In a device of the class described, the 30 combination with the sills of a car, of stationary stops secured thereon, stationary members between said stops, movable members mounted adjacent said stationary members, a series of interfitting abutments on 35 both said movable and stationary members to cause a diagonal movement of said movable members to take place toward one another when moved with respect to said stationary members, resilient means interposed 40 between said movable members to resist inward movement of one another toward one another, friction devices at each end of said movable members to resist relative movement therebetween in either direction, 45 and a yoke disposed about said movable members to impart movement thereto due to draft or buffing stresses imparted to the gear.

10. A draft gear comprising stationary 50 and movable friction elements, recessed blocks associated with said movable friction

elements, and eccentric means between said recessed blocks for adjustment for wear between said elements.

11. A draft gear comprising stationary 55 and movable friction elements, friction plates at the ends of said movable friction elements to assist in resisting movement of the gear parts, and eccentric means for adjustment for wear between the gear parts. 60

12. A draft gear of the class described comprising stationary and movable friction members, friction plates movable with said movable members, and resilient means for resisting movement of said movable members. 65

13. A draft gear comprising stationary members, a series of stationary abutments thereon, movable members associated therewith having a series of inclined abutments 70 interfitting with the abutments on said stationary members adapted to resist movement of said movable members toward one another with a movement in either direction longitudinally with respect to said stationary members, friction plates resisting movement of said movable members toward one another, and spring resisted wedge blocks interposed between said movable members to resist movement of said movable members toward one another. 75

14. A draft gear comprising stationary members, movable members associated therewith adapted to move with respect thereto resisted by friction, friction plates mounted 85 at each end of said movable members operating to resist movements thereof in either direction relative said stationary members, spring resisted friction means operating to resist movement of said movable members 90 toward one another, and eccentric means mounted at one end of the gear adjustable to take up for wear upon the parts within the gear.

In testimony whereof I have hereunto 95 subscribed my name in the presence of two subscribing witnesses.
